UNITED STATES PATENT OFFICE

2,605,882

DIPPING CONVEYER

Thomas H. Curtis, Red Bank, N. J., assignor to
 Hanson-Van Winkle-Munning Company, Matawan, N. J., a corporation of New Jersey

Application April 18, 1950, Serial No. 156,626

13 Claims. (Cl. 198—19)

1

This invention relates to processing machinery, and particularly to processing machinery having associated therewith devices selectively operable for modifying the operating cycle of the apparatus on at least some of the workpieces being treated thereby.

In my previously filed applications, Serial Nos. 92,838, filed May 12, 1949, 154,077, filed April 5, 1950, and 156,627, filed April 18, 1950, I have illustrated arrangements in connection with processing machines for selectively modifying the cycle thereof. The instant application is a further extension of the general thought embodied in these previous applications.

The problem being treated is, generally, as follows:

Automatic machines are provided for processing workpieces through chemical, mechanical, and electrolytic treatments. The particular work cycle with which the present invention is illustrated is a processing machine for conveying workpieces through chemical and electrolytic treatments. An example of such a treatment is the plating of various sorts of workpieces such as typewriter parts, automobile hardware, building hardware, valves, and many other types of work members. So long as there is sufficient volume of any one type of workpiece to maintain a processing machine in continuous operation, there is no need for the machine to have a flexible cycle. However, machines of this nature are capable of vast production and many times their utility could be materially enhanced if the operating cycle could be made sufficiently flexible to accommodate at one time workpieces requiring different types of treatment.

An example of workpieces requiring different types of treatment is to be found in connection with automobile hardware referred to above. This hardware consists of both inside and outside parts and it is desired that those on the outside carry a heavier plating deposit than those which are to be used on the inside because of the more severe weather conditions to which they are exposed.

In other cases, there may be two groups of parts to be processed, certain of which require one type of cleaning operations, and another of which requires another type of cleaning operations, as where the one group would require a bright dip in an acid tank and the other group would not require the bright dip.

The particular object of the present invention is to provide a processing machine modified in such a manner that it can handle a variety of different types of workpieces at the same time

2

and give each thereof the proper overall treatment.

Another object of this invention is to provide devices adapted for being associated with a processing machine of a more or less conventional type and which devices provide for a flexible cycle of operation of the machine whereby different types of workpieces can be operated on by the machine at the same time and receive selectively different types of treatment.

A still further object of this invention is the provision, in a processing machine having a plurality of workpiece carrying members, of devices associated with the machine and control means for the devices such that the said members will receive selectively different treatment during one complete cycle of operation of the machine.

It is also an object of this invention to provide a processing machine having a plurality of workpiece supporting members with devices controlled by the said members for determining the particular treatment the workpieces supported by the members receive during one complete cycle of operation of the machine.

These and other objects and advantages will become more apparent upon reference to the following description taken in connection with the accompanying drawings in which:

Figure 1 is a diagrammatic elevational view showing a portion of a processing machine having devices associated therewith in accordance with this invention.

Figure 2 is a sectional view indicated by line 2—2 on Figure 1 and showing one form which the device of this invention can take.

Figure 3 is a view similar to Figure 2 but showing a slightly different mechanical arrangement of the device.

Figure 4 is a view similar to Figures 2 and 3 but showing a still different arrangement of the device.

Figure 5 is a view indicated by line 5—5 on Figure 4 and showing the appearance of the device of Figure 4 from the front and also showing a bridge arrangement that forms a part of a construction of Figure 1.

Figure 6 is a view indicated by line 6—6 on Figure 4 showing a limit switch for controlling the device and a cam for controlling the limit switch actuating member.

Figure 7 is a view showing still another form of a device according to this invention.

Figure 8 is a view looking in at the device of Figure 7 from the front.

Figure 9 is a diagrammatic view showing the

electric control circuit for the device of Figures 7 and 8.

Figures 10 and 11 show a modified arrangement which operates in a manner similar to the device of Figures 7 and 8.

Figure 12 is a view showing a thruster arranged for actuating the device of Figures 7 and 8 and a control circuit therefor.

Figure 13 is a view showing a modified construction of a device which is somewhat similar to that illustrated in Figure 2 and Figure 3.

Figure 14 is a diagrammatic view showing how a photocell circuit could be utilized for controlling the several devices in place of the limit switch arrangements illustrated; and

Figure 15 is a perspective view showing still another modified arrangement for selectively holding the carrier arms in an elevated position.

General arrangement

In general, a processing machine of the type with which this invention is concerned comprises a frame 10 which provides upper and lower channels 12 and 14, respectively, in which conveyor chains 16 and 18 run. Connected to these conveyor chains and extending therebetween at spaced intervals therealong are the spaced vertical channels 20 that provide guides for the skate-like slide members 22. These slide members include the projecting arm parts 24 that serve as supports for the workpieces to be treated.

Vertically reciprocable in the frame is an elevator structure 26 that includes a lift angle 28 projecting to beneath the pick-up roller 30 on the back of slide member 22.

The conveyor chains and elevator are power-driven and are interlocked in such a manner that substantially all movement of the elevator takes place in the absence of movement of the conveyor chains and substantially all movement of the conveyor chains takes place while the elevator is in its uppermost position. In this manner the workpiece supporting arms are successively moved into a plurality of different work stations and may be lowered therein for treatment of the workpieces as required.

The means for treating the workpieces generally comprises a series of tanks as at 32 in Figure 1. These tanks may be of a size to embrace only a single work station, as those at 34, or may extend for two or more work stations, as at 36. When the tanks are only one work station in extent the workpieces are merely lowered therein and then raised from the tanks on the next upward movement of the elevator.

When the tanks extend over more than one work station, the workpieces are lowered into the tank at one end and then remain lowered through successive movements of the conveyor until they reach the other end of the tank where they are again engaged by the elevator and lifted upwardly.

According to this invention means are provided for selectively preventing the arms from being lowered at any one or more of the work stations whereby a complete tank or tanks or a portion of a tank or tanks can be bypassed thereby to vary the treatment of the workpieces on the arms. This is accomplished, according to this invention, by selectively interposing beneath some part of the work supporting arm or associated slide member an auxiliary element which will support this slide and arm when the elevator moves downwardly. These devices are controlled by adjustable means carried on the arms so that each arm

can be adjusted in accordance with the workpieces thereon to go through a new predetermined operative cycle.

Modification of Figure 2

In Figure 2 there is illustrated a device in accordance with this invention and which occupies the positions in Figure 1 identified by the reference numeral 38. The device consists of an auxiliary bracket 40 on frame 10 having slidably mounted thereon a plate 42 connected with a rod 44 normally urged by spring 46 to hold plate 42 in its dotted line position identified by numeral 48.

15 A solenoid S-1 is connected with rod 44 by lever 50 so energization of S-1 will move plate 42 into its full line position. Carried on the front side of slide 22 is an auxiliary roller 52 adapted for engagement on its underneath side by plate 20 42 when S-1 is energized.

Energization of S-1 is accomplished by closing of limit switch LS-1 by cam 54 adjustably mounted on arm 24. The adjustable mounting of cam 54 permits it to be moved into position to 25 engage switch LS-1 to move plate 42 into operative position thereby to hold the arm in its upper position, or the cam may be adjusted to miss the limit switch whereby the arm will move downwardly according to a normal cycle.

30 By placing the devices of Figure 2 at the positions 38 any one or more of the first four tanks or the first position of the last tank can be bypassed.

When the first position of the first tank, that 35 is the position at the extreme right end of the first tank, is not bypassed, the arm remains lowered during one movement of the conveyor chains and is then elevated at the position marked 56. At position 56 there is a bridge on the machine 40 frame which is shown in Figure 5 at 58 and which comprises a bridge plate 60 positioned to extend across an opening 62 in the elevator lift angle 28 when the elevator is up. Bridge plate 60 is normally urged down by springs 64 but will yield upwardly to its dotted line position 66 to admit the roller 30 of a work arm aligned therewith so that workpiece supporting arms which were lowered at the first work station of the tank will not be interfered with by the plate 60, whereas the 45 arms which were held in an elevated position at the first work station of the said tank will roll over bridge plate 60 as though the lift angle 28 were continuous.

For lifting the work arms that were lowered in 55 the first position of the first tank, when they are aligned with the said bridge, there is an auxiliary lift element or flipper 68 on the elevator fitting in the space or opening 62 of the elevator lift angle 28 which is normally positioned to engage 60 roller 30 but which will cam over the said roller when the elevator moves downward. A flipper of this nature is illustrated at 68 in Figure 2.

For lowering the work supporting arms at the 65 first station of the tank at the right end of Figure 1 when the hold out plate 42 is in its upper position, a somewhat different type of flipper than that referred to above is mounted on the elevator. A flipper of this type is illustrated at 70 in Figure 4 and comprises plate 72 normally held by springs 70 74 in position to receive roller 30 when the conveyor operates, but adapted for being moved out of alignment with the said roller by yielding plunger 76 mounted on frame 10 adjacent the lower position of the arm.

75 In this manner the elevator will receive the

arm in its upper position and then release it at its lower position.

In the foregoing it will be seen that by adjusting cam 54 on the associated carrier arm, the said arm may be conveyed through any of a number of different types of work cycles in one and the same machine.

Modification of Figure 3

In Figure 3 substantially the same structure is employed as was illustrated and described in connection with Figure 2 and the same reference numerals are appended to corresponding parts. In Figure 3, however, the hold out plate 78 is pivoted at 80 on auxiliary frame 40 and is normally urged by spring 82 into ineffective position. Energization of solenoid S-2 will move plate 78 about its pivot into effective position. The arrangement of Figure 3 is somewhat more compact and simpler to construct than the arrangement of Figure 2 but operates in a corresponding manner.

Modification of Figure 4

In Figure 4 there is shown an arrangement which is also quite similar to that of Figure 2 and to which the same reference numerals have been appended where applicable. In Figure 4 the principal difference is that the hold out plate 84 is adapted for engagement with roller 30 and thus the auxiliary roller 52 of Figures 2 and 3 is not necessary.

Hold out plate 84 is mounted on block 86 connected with rod 88 normally urged by spring 90 to hold the plate in its ineffective position. Energization of S-3 similarly to energization of S-1 will move the plate to its effective position.

The cam 54 shown in Figures 2, 3 and 4 is somewhat better illustrated in Figure 6 wherein it will be seen to comprise a rather elongated element which will engage limit switch LS-1 in advance of the movement of the associated workpiece supporting arm into the work station so that hold out plate, whether it be the type of Figures 2, 3 or 4, will have time to move into effective position before the arm is aligned therewith.

Modification of Figures 7, 8, and 9

In these figures there is shown a hold out arrangement wherein a rotatable column 90 is positioned adjacent the work station where it is desired selectively to prevent the workpiece carrying arms from moving downwardly. This column may be journaled in the spaced supporting bearing portions 92 and has on its upper end offset head portion 94 which in one position underlies the adjacent carrier arm and in another position is disposed to one side of the said arm.

One arrangement for rotating the column between its two positions comprises a worm wheel 96 on the column which is driven by a worm gear on the shaft of a reversible motor 98. The limits of movement of the column may be determined by the limit switches LS-2 and LS-3 which are adapted for being engaged by finger 100 on the column at the two operative positions of the column.

Similarly, as with the modifications previously described, there is a limit switch adapted for selective actuation by the workpiece supporting arms. This limit switch is indicated at LS-4 and is characterized in that it has a pair of normally closed contacts and a pair of normally open contacts. A cam 102 carried on the workpiece sup-

porting arm is adapted for selective engagement with the limit switch in the manner already described in connection with Figure 6.

The control circuit for motor 98 and including limit switches LS-2, LS-3 and LS-4 is shown in Figure 9. In this view it will be seen that when limit switch LS-4 is in its actuated position the blade thereof which is in series with limit switch LS-2 is closed. This energizes motor 98 to run in a direction to turn column 90 to position its offset head as shown in Figure 8 so as to support the workpiece carrying arm. Movement of the column continues until switch LS-2 is opened thereby de-energizing and halting the motor.

Thereafter, when the conveyor again moves so that cam 102 runs off limit switch LS-4, the blade thereof in series with limit switch LS-3 will be closed and motor 98 will be energized to run in the opposite direction. This movement of the motor will continue until finger 100 engages and opens switch LS-3 thereby again de-energizing and halting the motor.

It will be seen that the described arrangement provides means for selectively supporting the arms in their elevated positions at any selected ones of the work stations of the machine.

In Figure 12 there is shown a somewhat modified manner of actuating column 90 between its two positions. In Figure 12 there is a thruster 104 which may be electric, hydraulic, pneumatic, or a combination thereof as desired, which is connected with column 90 as illustrated. For controlling thruster 104, a cam 106 on arm 24 is adapted for engagement with a limit switch LS-5 thereby to energize coil 108 of a contactor having a first blade 110 which establishes a holding circuit for the coil through normally closed limit switch LS-6, and also having a blade 112 in series with thruster 104. If cam 106 is adjusted to engage and close switch LS-5 as the arm moves into the associated work station, then the contactor remains energized until after the conveyor again operates to carry arm 24 into position for its cam 106 to engage and open limit switch LS-6. It will be evident that the arrangement illustrated in Figure 12 is quite similar to that described in connection with Figures 7 through 9.

Modification of Figures 10 and 11

In Figures 10 and 11 there is shown a construction which operates similar to that of Figures 7 and 8 but wherein the bulky and expensive column construction is eliminated. In Figures 10 and 11 an auxiliary bracket 114 is mounted on the machine frame and pivoted thereon is a hook 116 adapted for hooking around the workpiece supporting arm as shown in Figure 10, or for being sprung out of the path of the said arm by spring 118 as shown in Figure 11. A solenoid S-4 is energizable through the medium of limit switch LS-7 and cam 120 in the manner previously described in connection with the other modifications.

Due to the fact that the work carrying arm settles downwardly somewhat when the elevator moves down following a conveying movement, it is preferable that the cam 120 present a substantially vertical switch actuating surface whereby the said settling downwardly of the arm will not bring about de-energization of solenoid S-4. At the same time sufficient freedom of movement of the arm of the limit switch may be had to permit the cam to pass therebeneath when conveyor movement is again resumed.

Modification of Figure 13

In Figure 13 there is shown a modification which is quite similar to those of Figures 2, 3 and 4 in that an auxiliary hold out member 122 is arranged for being selectively moved to beneath a roller connected with the workpiece supporting arm and its supporting slide. In Figure 13, however, member 122 is pivoted at 124 and has an actuating lever 126 urged in a direction to move member 122 to its ineffective position by spring 128, and adapted for being moved in a direction to place member 122 in effective position by energization of a solenoid S-5. As in connection with the other modifications there is provided a limit switch LS-8 and an actuating cam therefor 130 adjustably mounted on the workpiece supporting arm.

In connection with the modifications of Figures 2, 3 and 13 wherein the auxiliary roller 52 is employed, the hold out members may be aligned with a hold out track, if desired, so that the workpiece supporting arms engaged by the said hold out members could be maintained in an elevated position for one or more further cycles of operation of the conveyor by the hold out track, if so desired.

Modification of Figure 14

In Figure 14 there is illustrated a simple photocell control circuit which could be utilized in place of any of the limit switches previously described. In Figure 14 there is a light source 150 that normally illuminates photocell 152. The photocell is in circuit with a battery 154 and a resistor 156 and when illuminated permits the battery to cause current to flow through the resistor in the direction of arrow 158.

Resistor 156 is in the grid to cathode circuit of a relay tube 160 which circuit includes also the biasing battery 162. When current is flowing through resistor 156 it holds the grid negative relative to the cathode and prevents discharge of tube 160. However, when resistor 156 is not conducting current, battery 162 will bias the grid relative to the cathode so tube 160 does discharge and energizes relay coil 164 in the plate circuit of the tube.

Energization of the relay will cause its contacts 166 to close or open as desired and it will be evident that these contacts can be placed in any of the several arrangements described in place of any of the mechanically operated limit switches shown.

The photocell 152 is selectively made conductive or non-conductive by the flags 168 adjustably mounted on the workpiece supporting arms or their associated slides so that the same degree of selectivity of operation of the relay obtains that obtains in connection with the mechanically operated limit switches.

Modification of Figure 15

In Figure 15 there is shown still another modification wherein there is a block 200 freely vertically slidable on the guide rods 202 which are suitably fixedly supported in the frame of the machine. Block 200 carries an angle clip 204 that is receivable in a gap in the lift angle of the elevator. A bar 206 connected with angle clip 204 extends over the elevator lift angle 70 whereby when the elevator comes up the angle clip and its supporting block will also be elevated.

Secured to block 200 is a bracket 208 having a pivot pin 210 on which is pivotally mounted latch arm 212. The upper end of latch arm 212 is

adapted for hooking over a fixed element, such as the support plate 214, when block 200 and angle clip 204 are raised to their highest position by the elevator. A spring 216 urges the latch arm toward the position in which it is illustrated in Figure 15.

The latch arm is adapted for being selectively disengaged by a cam 218 adapted for engagement with roller 220 on the lower end of the latch arm. Cam 218 is adapted for being adjustably mounted on the screws 222 extending through slots 224 in the cam.

One of the cams 218 is provided for each of the carrier members it is desired selectively to set down in the various treatment positions that have associated therewith the slidable blocks 200 and angle clips 204. By adjusting the cams on the arms so they will engage the rollers 220, the associated work members will be set down in the normal manner. However, by adjusting the cam so that it will not strike the roller 220 or by removing the cam from the carrier member, the latch arm will remain effective for supporting the block and angle clip and in this manner prevent the associated work member from being set down.

It will be apparent that the latch arm could be normally engaged as shown, or could be normally disengaged with the cams being employed for selectively moving the latch arm into engagement. Similarly, while mechanical means are shown whereby the latch arm is directly actuated by the cam, it will be evident that pneumatic, hydraulic, electrical, or electronic means could be employed for detecting the setting of the cam and providing the actuating force for moving the latch arm to its proper position.

It will be understood that this invention is susceptible to modification in order to adapt it to different usages and conditions and, accordingly, it is desired to comprehend such modifications within this invention as may fall within the scope of the appended claims.

I claim:

1. In a machine having a movable work member, a conveyor for moving said member in a horizontal direction, an elevator for moving said member in a vertical direction on said conveyor, stationarily supported hold-out means movable into engagement with said member for supporting it and thereby preventing its movement by said elevator, and means controlled by movements of said member by said conveyor for selectively moving said hold-out means between its effective and ineffective positions.

2. In a processing machine having a plurality of work stations, a work member, a conveyor on which the work member is vertically slidably intermittently operable for conveying said member to successive work stations, an elevator operable alternately with said conveyor for lifting said work member for a conveying movement and for setting said member down when the conveyor is halted, a hold-out member selectively adjustable for engagement with said work member to support the work member during downward movement of said elevator, and means controlled by said work member for selectively making said hold-out member effective or ineffective.

3. In a processing machine having a plurality of work stations, a work member, a conveyor on which said member is vertically slidable, intermittently operable for conveying said member to said work stations in succession, an elevator operable alternately with said conveyor for lifting

said member for a conveying movement and for setting the member down when the conveyor is halted, a hold-out member at one of said work stations normally positioned to permit the work member to move down with said elevator, and means on the work member selectively adjustable for making said hold-out member effective for preventing movement of said work member with said elevator.

4. In a processing machine having a frame and a plurality of work stations, a conveyor on said frame, a work member connected with the conveyor and vertically slidably thereon, an elevator operable for raising and lowering said work member on said conveyor, said conveyor being intermittently operable to convey said member to said work stations in succession and said elevator being operable alternately with the conveyor so the work member is held up during a conveying movement and is then set down in the work stations and lifted therefrom while the conveyor is halted, a hold-out member movably mounted on the frame at one of said work stations, actuating means for moving said hold-out member between effective and ineffective positions, and means on the work member for controlling said actuating means.

5. In a processing machine having a frame, a plurality of work stations, a work member, a conveyor on which the work member is vertically slidable for conveying the work member to said work stations in succession, and an elevator for raising the work member for conveying movement thereof and for lowering the work member when the conveyor is halted, a hold-out member on the frame at one of said work stations normally positioned to permit the work member to move down with the elevator at that station, actuating means for moving said hold-out member between effective and ineffective positions, and means on said work member adjustable into position to cause said actuating means to move said hold-out member into effective position in response to movement of said work member into the said work station.

6. In a processing machine having a frame, a plurality of work stations, a work member, a conveyor on which the work member is vertically slidable for conveying the work member to said work stations in succession, and an elevator for raising the work member for conveying movement thereof and for lowering the work member when the conveyor is halted, a hold-out member on the frame at one of said work stations normally positioned to permit the work member to move down with the elevator at that station, actuating means for moving said hold-out member between effective and ineffective positions, means on said work member adjustable into position to cause said actuating means to move said hold-out member into effective position in response to movement of said work member into the said work station, and means responsive to movement of said work member out of said work station for causing said hold-out member to move to its ineffective position.

7. In a processing machine having a frame with a horizontally movable conveyor and a vertically movable elevator and a work member connected with the conveyor for movement therewith and vertically reciprocable thereon for movement with the elevator, said conveyor being intermittently operable for conveying the work member to a plurality of work stations and said elevator being operable alternately to said conveyor so as to lower and raise the work member while the con-

veyor is halted and to hold the work member elevated while the conveyor is moving, a part projecting from said work member, a supporting member on the frame at one of said stations adapted for engagement with said projecting part when the member is lifted, and actuating means responsive to movement of said member into said work station for moving said supporting member into effective position.

8. In a processing machine having a frame and a plurality of work stations, a plurality of work members comprising workpiece supporting devices, a conveyor in the frame to move said members from station to station, an elevator for vertically reciprocating said members on the conveyor, said conveyor and elevator operating alternately so conveying takes place only while the elevator is up, a hold-out member on said frame at at least one work station adapted in its effective position to engage the work member at that station and to support it while the elevator goes down, said hold-out member also having an ineffective position, means urging said hold-out member toward its ineffective position, actuating means energizable for moving said hold-out member into its effective position, and means adjustably mounted on said work members for selectively energizing said actuating means in response to the movement of said members into said one work station and for de-energizing said actuating means in response to the movement of said work members out of said one work station.

9. In a processing machine having a frame and a plurality of work stations, a plurality of work members, a conveyor to move said members from station to station, an elevator engageable with the members from beneath for raising and lowering the members on the conveyor, said conveyor and elevator operating alternately so conveying only takes place while the elevator is up, a hold-out plate movable on said frame at one of the work stations and adapted in one position to engage the work member in that station to support it while the elevator goes down, a spring urging the plate out of the said one position, and actuating means selectively responsive to movement of the said work members into said one station for moving said hold-out plate into its effective position.

10. In a processing machine having a frame and a plurality of work stations, a plurality of work members, a conveyor to move said members from station to station, an elevator engageable with the members from beneath for raising and lowering the members on the conveyor, said conveyor and elevator operating alternately so conveying only takes place while the elevator is up, a projecting portion on each of the work members, and a hold-out plate movably mounted on the frame having a first position where movement of the work members into the said one work station will bring the projecting parts thereof into engagement with the hold-out member, said hold-out member having a second position out of the path of said parts, electrical means energizable to move said hold-out member into its first position, a switch for energizing said electrical means, and cams adjustably mounted on said work members for selective engagement with said switch as the said work members move into said one station.

11. In a processing machine having a frame and a plurality of work stations, a plurality of work members, a conveyor to move said members from station to station, an elevator engageable

11

with the members from beneath for raising and lowering the members on the conveyor, said conveyor and elevator operating alternately so conveying only takes place while the elevator is up, a hold-out member at one of said work stations comprising a hook-like element pivotally connected with said frame normally positioned to permit the work members to move with the elevator, electrical means energizable for moving said hook-like element into supporting engagement with a work member in elevated position in the said one station, a switch for controlling said electrical means, and cams adjustably mounted on said work arms for selectively actuating said switch as said work members are conveyed in elevated position into said one station.

12. In a processing machine having frame and a plurality of work stations, a plurality of work members, a conveyor to move said members from station to station, an elevator engageable with the members from beneath for raising and lowering the members on the conveyor said conveyor and elevator operating alternately so conveying only takes place while the elevator is up, a hold-out member at one of said stations comprising a vertical column having an offset head at the upper end below the upper position of said work members and being rotatable into effective position to present the said head to the underneath side of a work member in elevated position in the said station to support the work member when the elevator goes down, and means adjustably mounted on said work member selectively operable by the movement of said work members into said one station for controlling the rotation of said column into said effective

12

position each such work member also being operable to cause return of said column to ineffective position upon movement of the arm out of said one station.

- 5 13. An arrangement as claimed in claim 5 in which the said actuating means for moving the hold-out member between effective and ineffective positions comprises electrical means, a photoelectric control circuit for controlling said electrical means, and the said means on said work member adjustable into position to cause such actuating means to move said hold-out member into effective position in response to movement of said work member into the said work station comprising a mask adjustably carried by the said work member so as to be selectively positionable into position to cause a change in the illumination of the photocell of the said photocell control circuit as the work member moves into operative position relative to the said hold-out member.
